JOSEPH H. SHEARD, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA

AWNING

Application filed June 22, 1928. Serial No. 287,381.

This invention relates to awnings of the demountable and collapsible or unfolding type such as ordinarily used for windows or doors.

The application of awnings to windows or doors, particularly those of metallic construction, has been comparatively expensive heretofore in that it necessitated employment of skilled mechanics, as well as use of special tools, for the purpose.

My invention is directed in part toward overcoming the drawbacks pointed out, which end I attain by incorporating in the window or door structure, incidental to its manufacture, the necessary means for attaching the awning.

In general, I aim to afford an awning of simple and inexpensive construction, capable of ready and easy hanging and dismantling without requiring special tools, that is sturdy and secure against rattling and displacement under wind pressure when in lowered position; and which, moreover, is wholly collapsible for protection within the confines of the associated opening when not in use.

In the drawings, Fig. I is a perspective view showing a vertical sectional view through a metallic window structure suitably modified in accordance with this invention for attachment of my novel awning.

Fig. II is a fragmentary perspective view showing in detail the means employed in securing the covering of the awning along its upper edge to the head rail of the window frame.

Fig. III is an inverted perspective view of one of the parts shown in Fig. II.

Fig. IV is a fragmentary perspective view showing one of the pivot brackets for the bracing frames of the awning.

Figs. V and VI are, respectively, a plan and side elevation showing a cleat for the awning operating cord or rope and the manner in which the same is attached.

Figs. VII and VIII are, respectively, front and side elevations of a hook and its fastening means whereby the awning is secured against rattling and displacement under wind pressure when in lowered position.

With reference first more particularly to

Fig. I of these illustrations, the window structure there delineated comprises a fixed frame 10 which is set into the opening 11 provided for it in the masonry 12 of the building, after a manner commonly practiced in this art. 55 The frame 10 has a top or head rail 13, as well as bottom and side jamb rails 14, 15, respectively, in the present instance, all of metallic angular cross section. Secured in the upper part of the frame 10 is a fixed window light 16, while the lower part is occupied by a glazed sash 17 which may be pivoted to swing open on either a horizontal or vertical axis, not illustrated. The sash 17 is also constructed with metallic perimetric rail bars of 65 angular cross section which close weather tight all around, against the rails 14, 15 of the fixed frame 10, as well as against an intermediate or cross rail 18 of the latter.

The head rail 13 of the fixed frame 10 has a frontal projection 20 adapted to extend somewhat beyond the masonry 12, as shown in Fig. I, for service as a weathering or rain drip. This projection may be integrally formed with the rail 13, or, as herein shown, made as a separate piece fashioned from sheet metal with an angular bend at 21 (see Fig. II) to fit the cross section of said rail; and permanently secured in place incidental to manufacture of the window frame 10, either by 70 riveting or welding, as found most expedient in practice. Referring again to Fig. II, it will be observed that the projection 20 affords along its under side, in conjunction with a separately attached longitudinally extending 75 strip 22, a co-extensive counter-recessed slot 23 with a lateral cut out 24, see Fig. III, for a purpose which will be presently explained.

With reference now to the awning which is comprehensively designated by the numeral 90 25 in Fig. I, it will be observed that the same comprises a covering 26, which, along its upper edge is pierced and grommeted at intervals, as at 27 in Fig. II, for passage of securing means in the form of screws 28 with 95 heads 29. In attaching the awning to the window frame 10, the head ends 29 of the screws 28 are inserted successively through the lateral cut out 24 in the projection 20; and said screws are thereafter slid into prop- 100

erly allocated positions along the slot 23. Wing nuts 30 are subsequently applied to the screws 28 to clamp the latter to the head rail projection 20 with the upper edge of the awning covering 26 interposed. The covering 26 is otherwise supported by bottom and intermediate bracing frames 31, 32, which are both fashioned to U-shape configuration from stout wire or rod stock. The side arms of these frames 31, 32 are flattened at their ends and pierced, as shown in Fig. IV, for pivotal attachment to brackets 33 whereof one is shown in detail in the latter figure and also indicated in Fig. I. These brackets 33 are preferably made as castings with rearwardly extending tongues 33a adapted to be permanently attached to each of the side verticals or jambs 15 of the fixed window frame 10 by riveting or welding, also incidental to initial manufacture of said frame. The projecting portions of the brackets 33 are clevised as at 33b to receive the flattened ends of the side arms of the frames 31, 32, pivotal attachment being effected by means of screws 34, 35, see 25 Fig. IV. It is to be particularly noted that the pivot centers 34, 35 lie in different planes so that interference is avoided between the frames 31, 32 as the awning 25 is collapsed or folded.

30 To insure the frames 31, 32 against rattling and also to firmly hold the awning 25 as a whole against displacement under wind pressure, when lowered, I provide angular struts having, as shown in Figs. I, VII and VIII, the form of hooks 36, one such hook being associated with each side arm of the frame 31. These hooks 36 are attached, at intermediate points to the side arms of the frame 31, by means of two piece clips 37 with capacity for free swinging movement about spacing collars 38 associated with screw bolts 39 by which said clips are clamped in position. For cooperation with the hooks 36 the side jamb rails 15 of the fixed window frame 10 are provided, at a level below the brackets 33, with permanently attached eyes 40, see Fig. I.

The operating means for the awning 25 may include a cord or rope 40 guided over 50 suitable pulleys (not shown) and secured at the ends to the lower bracing frame 31 of said awning. For convenience in anchoring the cord or rope 41, I attach to one of the side arms of the frame 32 a cleat, such as shown 55 at 42 in Fig. I and detailed on a larger scale in Figs. V and VI. The cleat 42 is secured to the side arm of the frame 32 by a two piece clip 43—similar to the clips 37 aforescribed—which is clamped in position by 60 screws 44 with associate spacing collars 45, in a manner obvious from the illustration. To raise the awning 25 the hooks 36 are first disengaged from the eyes 40, and the frames 31, 32 swung upward by pulling on 65 the rope or cord 41 until said frames assume

an upright position. It is noteworthy in this connection from Fig. I that the pivot centers for the frames 31, 32 are well within the window opening 11 whereby the awning 25, when raised is wholly protected within said opening to the avoidance of any projecting parts beyond the wall surface of the building 12. By attaching the cleat 42 to the awning 25 instead of the window frame 10, it will be apparent that I avoid an unnecessary 70 and unsightly projection or obstruction on the window during the seasons of the year when the said awning is removed. Of those parts which do remain on the window, the brackets 33 and the screw eyes 40 are small 75 and inconspicuous, while the projection 20 of the head rail 13 is of use in that it functions as a weathering or rain drip.

I have thus provided a very simple and efficient awning wholly attached to metal window frames with provisions which permit ready mounting and dismantling as required in accordance with the changing seasons of the year, such mounting and dismantling being effected without necessitating 80 employment of skilled mechanics nor use of special tools.

Having thus described my invention, I claim:

1. In an awning for metal frame structures of the type described, a plurality of swingable brace members to support the shelter covering with pierced ends, and brackets having pivots for attachment of the pierced ends, said bracket pivots being allocated to different planes and also embodying rearward extensions for connection to opposing jamb rails of the frame structure whereby the awning, as a whole, may be collapsed within the confines of the frame structure 105 opening.

2. In an awning for metal frame structures of the type described, a plurality of swingable brace members to support the shelter covering with pierced ends, brackets having pivots for attachment of the pierced ends, operating means including a cord, and a cleat for the same secured to one of the brace members, said bracket pivots being allocated to different planes and also embodying rearward extensions for connection to opposing jamb rails of the frame structure whereby the awning, as a whole, may be collapsed within the confines of the frame structure 110 opening.

3. In an awning for metal frame structures of the type described, a plurality of swingable brace members to support the shelter covering with pierced ends, brackets having pivots for attachment of the pierced ends, operating means including a cord, and a cleat for the same secured to one of the brace members, in combination with angular struts pivotally secured at intermediate points to the side arms of another of the brace mem- 115 120 125 130

- bers for engagement with means on the side jambs at a level below the brackets aforesaid, and said bracket pivots being allocated to different planes and also embodying rear-
ward extensions for connection to opposing jamb rails of the frame structure whereby the awning as a whole, may be collapsed within the confines of the frame structure opening.
- 10 4. A pivot bracket in accordance with any one of the preceding claims embodying a clevised portion having pivot centers in different planes to receive the brace member ends, and a rearwardly extending tongue appropriately configured for permanent attachment to the side jambs of the frame structure.

In testimony whereof, I have hereunto signed my name at Philadelphia, Pennsylvania, this 12th day of June, 1928.

JOSEPH H. SHEARD.
